UNITED STATES PATENT OFFICE.

AUGUST ARENS, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,033,059.

Specification of Letters Patent. Patented July 16, 1912.

Application filed February 8, 1912. Serial No. 678,172.

To all whom it may concern:

Be it known that I, AUGUST ARENS, a citizen of the United States, residing at New Britain, Hartford county, State of Connecticut, 5 have invented certain new and useful Improvements in Locks, of which the following is a full, clear, and exact description.

My invention relates to locks, and is particularly concerned with locks adapted for 10 use on corridor doors of hotels, etc.

It includes in connection with the usual dead bolt customarily operated from the outside by a series of keys—such as the guest or change, master, grand-master, display 15 and emergency keys—means operable only from the inside, which will project a second bolt, and which, if the first dead bolt is also projected, may be operable to retract both bolts to permit the door to be opened, and 20 which furthermore will permit the second bolt being retracted by the use of a certain key, which I will term the "emergency" key.

More specifically, the invention consists 25 in providing in connection with the second bolt, operating means therefor which will actuate the tumblers of all bolts at the same time and permit the projection and retraction of said bolts as hereinafter explained.

30 With these objects in view, the invention consists in the construction and arrangements of parts, a preferred embodiment of which is illustrated in the accompanying drawings, in which,

35 Figure 1 is a view in elevation of the lock with the cover plate removed to show the interior mechanism and with all bolts, with the exception of the latch bolt, retracted. Fig. 2 is a similar view showing the inside 40 bolt projected. Fig. 3 is an end elevation of the lock showing the face plate. Fig. 4 is an elevation of a detail. Figs. 5 and 6 are respectively face elevations and top plan views of a tumbler actuating lever. Fig. 7 45 is a plan view of a tumbler connecting bar.

Referring to the drawings by numerals, 1 indicates the lock case, 2 the face plate and 3 indicates what I will term the "first" dead bolt. 4 represents the "second" dead bolt 50 and 5 the ordinary latch bolt operable by means of the roll-back 6 through a knob spindle (not shown). The first dead bolt 3 is operated directly by keys inserted from the outside through a keyhole in the cover

plate, the aperture for the stumps of such 55 keys being indicated at 7 in the back plate of the casing. This first bolt is provided with a plurality of locking tumblers, such as 8, having the usual gate 9 coöperating with the fence 10 carried by said bolt 3. 60 Some of the tumblers 8 are provided with rear extensions 11 which rest upon the upper end of a tumbler connecting bar 12. Others of these tumblers are provided with rear extensions 13 (shown in dotted lines, as only 65 the lowest or bottom tumbler is shown in the drawing) which engage a slot 14 in the upper end of the connecting bar.

As I have before stated, the tumblers of the first dead bolt are preferably designed 70 for operation by a series of keys in a manner well known in the art. The specific construction of these tumblers forms no part of the present invention, it being essential, however, that the tumblers be provided with 75 means for engagement with the connecting bar 12, the other features described being common and well known in the art.

The connecting bar 12 is suitably guided in the case for longitudinal movement and 80 extends longitudinally of said case and at its lower end is formed with a transverse extension 15 which extends in between pins or lugs 16 formed on the free end of a pivoted tumbler operating lever 16 whose specific 85 construction and operation will be more fully described hereinafter.

The second dead bolt 4 is provided with the usual fence 17 and with a tumbler 18 gated at 19 to coöperate with said fence in 90 the usual manner. This tumbler may be operated by the usual key inserted from the inside through the keyhole 20. This tumbler 18 is provided at its free end with an extension 21 engaging in a slot 22 formed 95 in the connecting bar 12 intermediate its ends. A walking-beam lever 23 is connected at one end to the second dead bolt 4 and has the usual connection at its other end with the first dead bolt 3. The second dead 100 bolt, therefore, owing to this connection, may be projected without projecting the first dead bolt. Projection of the latter, however, after the second dead bolt has been projected, will retract said second dead bolt, and the first dead bolt, owing to its limited free connection with the end of lever 23, can then be retracted without 105

again projecting the second dead bolt whereby access may be had to the room. It is obvious that lifting the tumblers of either one of the bolts operates to raise the connecting bar 12 and the tumblers of the other bolt whereby said action is possible.

I have heretofore stated that the first dead bolt and its tumblers are of the type operable by a series of keys, such as so-called 10 change, master, grand-master, display and emergency keys, the display being bitted so that when said bolt is projected by it, no key except the display key, or the emergency key, can retract the same. The emergency key is so bitted that when the first 15 dead bolt is projected by it, no other key can retract the same. These features are well-known in the art.

In order to prevent unlocking of the door 20 from the outside by means of any key other than the emergency key when the door is locked from the inside, the dead bolt 4 is formed with a ward 24 at its rear end, which, when the said bolt is projected, takes 25 a position in line with the outer keyhole and consequently blocks the full insertion of the other keys mentioned, by reason of their biting. The biting of the emergency key, however, is such that when it is inserted from the outside, it will clear the 30 ward 24 and consequently can be fully inserted and turned to retract the second dead bolt 4 by first projecting the dead bolt 3. Then by retracting the bolt 3, the door will 35 be unlocked as heretofore described.

I have stated that the second dead bolt is adapted for operation by a key inserted from the inside through the keyhole 20. I provide, however, additional means which 40 will not only operate the second dead bolt in both directions independently of a key, but which will also directly lift the tumblers of both dead bolts to permit this action. To this end I provide below the dead 45 bolt 4 a bolt actuating member 25 which may, if desired, be formed as a third dead bolt, as indicated by dotted lines. As in the case with the two upper bolts, this member 25 slides in suitable guides in the lock case 50 and is further provided with an upper extension 26 fitting in a notch 27 formed in the lower edge of bolt 4. Pivoted at one end on this member 25 is the tumbler lever 16 having the usual tumbler spring abutting 55 against a lug 28 formed on the part 25 and normally holding the lever thrown downwardly. At its outer or free end, this lever member is recessed to permit of the insertion therethrough of a thumb turn hub 60 29 carrying at its inner end rock arms 30. A pin or lug 31 extends from the rear face of the lever member 16 and is adapted to be engaged by cam faces 32 on the rock arms 30 when the latter are rocked by rotating 65 the thumb turn hub 29 in either direction.

I have heretofore stated that the tumbler lever 16 at its lower end is provided with lugs 16^a between which rest the transverse extension 15 of the tumbler connecting bar 12. It is obvious that by rocking the thumb turn hub 29 either way, a cam face 32 will contact with the pin or lug 31 and thereby raise the tumbler lever 16. This movement of the tumbler lever will raise the tumbler connecting bar 12 which, by reason of its connection with the tumblers of both the first two dead bolts, will raise their tumblers to permit said bolts to be projected or retracted.

The rock arms 30 on the thumb turn hub 29 are adapted to project and retract the dead bolt 4, and to this end, the member 25 adjacent its inner end, is provided with a lug 33 which lies in the arc of movement of the ends of rock arms 30 so that when these arms have been rocked to lift the tumbler connecting bar 12, a further rotation will bring the end of one of the bars against one side, or the other, of this lug 33 and move the member 25 from its position as shown in Fig. 1 to the left or forwardly as shown in Fig. 2, or vice versa, to project or retract the dead bolt 4 through the connection therewith of the extension 26. This projecting and retracting operation of the rock arms will be clear from Figs. 1 and 2 of the drawings, in which, respectively, the rock arms are shown in bolt retracted and projected position with reference to the lug 33.

To recapitulate briefly, the operation of my lock is as follows: An occupant of a room who is desirous of protecting himself from intrusion may, either by means of his key or by the inside thumb turn, project the second dead bolt 4. If, while thus locked in, some one on the outside should endeavor to enter the room or apartment, the ward 24 of the dead bolt 4 will prevent any key, excepting the emergency key, from fully entering the lock case and thereby prevent said key from operating the tumblers. The proprietor, however, can, in case of emergency, use his emergency key and operate the tumblers of the first dead bolt 3 and first project the same, thereby retracting the inside dead bolt and then retract the same and enter.

In case the dead bolt 3 should be projected while there is an occupant within the room or apartment, the latter may freely unlock the door either by a key, or the thumb turn if the key is not available or misplaced.

For convenience of expression I may refer in the claims to the first dead bolt 3 as the outside dead bolt and the second dead bolt 4 as the inside dead bolt, because in the lock shown the first bolt is projected by a key inserted in the lock from the outside, and the second bolt is projected by a key or by a thumb turn at the inside.

While I have described a specific embodiment of my invention, it is obvious that the same is susceptible to many modifications.

What I claim is:

5. 1. In a lock, two bolts arranged to be independently projected by keys inserted from opposite sides of a door, a connection between said bolts whereby the projection of one will retract the other, an auxiliary means operable from one side of the door only for projecting and retracting one of said bolts independently of a key, tumbler mechanism for each of said bolts, a connection between said tumbler mechanisms whereby the proper positioning of one of said tumbler mechanisms will simultaneously properly position the other tumbler mechanism, and a connection between said auxiliary bolt controlling means and said 10 tumbler connecting mechanism whereby both of said bolts may be operated by said auxiliary operating means. 15
2. In a lock, two bolts arranged to be independently projected by keys inserted from opposite sides of a door, a connection between said bolts whereby the projection of one will retract the other, an auxiliary bolt operable from one side of the door only for projecting and retracting one of said first 20 two bolts independently of a key, tumbler mechanism for each of said bolts, a connection between said tumbler mechanisms whereby the proper positioning of one of said tumbler mechanisms will simultaneously properly position the other tumbler mechanism, and a connection between said auxiliary bolt and said tumbler connecting mechanism whereby both of said first two 25 bolts may be operated by said auxiliary operating bolt. 30
3. In a lock, a plurality of bolts including key-operable outside and inside dead bolts, a connection between said dead bolts whereby the projection of one will retract the other, tumbler mechanisms for each of said dead bolts, a connection between said tumbler mechanisms whereby an inside or outside key will actuate simultaneously said tumbler mechanisms and permit the projection and retraction of said dead bolts, and means 35 operable only from one side of the door and independent of a key for actuating said tumbler connection whereby both of said dead bolts may be operated by said independent means. 40
4. In a lock, a plurality of bolts including key-operable outside and inside dead bolts, a connection between said dead bolts whereby the projection of one will retract the other, tumbler mechanisms for each of said dead bolts, a connection between said tumbler mechanisms whereby an inside or outside key will actuate simultaneously said tumbler mechanisms and permit the projection and retraction of said dead bolts, means operable 45
- from the inside of the door only and independent of a key for actuating said tumbler connection whereby both of said dead bolts may be operated by said independent means, and means whereby a certain key operable from the exterior of the door may retract said inside dead bolt when projected. 50
5. In a lock, two bolts arranged to be independently projected by keys inserted from opposite sides of a door, a connection between said bolts whereby the projection of one will retract the other, an auxiliary bolt-actuating member operable from one side of the door only for projecting and retracting one of said bolts independently of a key, 55 tumbler mechanism for each of said bolts, a connection between said tumbler mechanisms whereby the proper positioning of one of said tumbler mechanisms will simultaneously properly position the other tumbler mechanism, an operating member for said tumbler connection, and actuating means coöperating with said tumbler operating member and with said bolt-actuating member to properly position said tumbler mechanisms and to actuate said bolts. 60
6. In a lock, the combination of a key-operable outside dead bolt, a key-operable inside dead bolt, a connection therebetween, tumbler mechanism for each of said bolts, a tumbler bar connecting each of said tumbler mechanisms, a bolt-actuating member auxiliary to said inside key operatively connected with said inside dead bolt, a pivoted tumbler-actuating lever having operable 65 connection with said tumbler bar, and means coöperating with said lever and bolt-actuating member adapted to lift said tumbler bar and actuate simultaneously the tumbler mechanisms connected therewith and adapted to move said bolt-actuating member to project and retract said inside dead bolt and also to retract said outside dead bolt when projected. 70
7. In a lock, the combination of an outside dead bolt, a key-operable inside dead bolt, a connection therebetween, tumbler mechanism for each of said bolts, a bar connecting both of said tumbler mechanisms, an extra inside dead bolt connected with said first mentioned inside bolt, a pivoted tumbler actuating lever, an operable connection between said lever and said tumbler bar, and means operable from inside the door coöperating with said lever and extra 75 inside bolt and adapted to actuate simultaneously said tumbler mechanisms and to project and retract both of said inside bolts, and also to retract said outside bolt if projected. 80
8. In a lock, two bolts arranged to be independently projected by keys inserted from opposite sides of a door, a connection between said bolts whereby the projection of one will retract the other, an auxiliary bolt- 85

- 4
- actuating member operable from one side of the door only, for projecting and retracting one of said bolts independently of a key, tumbler mechanism for each of said bolts, a 5 connection between said tumbler mechanisms whereby the proper positioning of one of said tumbler mechanisms will simultaneously properly position the other tumbler mechanism, a pivoted tumbler operating lever operatively connected with said tumbler connection, and a rotatable actuator cooperating with said pivoted lever and said bolt-actuating member and constructed and arranged so that a partial rotation will properly 10 position said tumbler mechanisms, and a further rotation will operate said bolt-actuating member to project or retract a bolt.
9. In a lock, two bolts arranged to be independently projected by keys inserted from opposite sides of a door, a connection between said bolts whereby the projection of one will retract the other, an auxiliary bolt operable from one side of the door only for 15 projecting and retracting one of said two bolts independently of a key, tumbler mechanism for each of said first two bolts, a connection between said tumbler mechanisms whereby the proper positioning of 20 one of said tumbler mechanisms will simultaneously properly position the other tumbler mechanism, a pivoted lever operatively connected with said tumbler connection and having an abutment formed thereon, an 25 abutment formed on said auxiliary bolt, and 30
- 35
- a rotatable actuator operable from one side of the door only independently of a key and provided with arms adapted to engage with said lever and auxiliary bolt abutments, said arms being constructed and arranged so that a partial rotation will properly position said tumbler mechanisms, and a further rotation will operate said auxiliary bolt member to project or retract a bolt. 40
10. In a lock, a plurality of bolts including key-operable outside and inside dead bolts, a connection between said dead bolts whereby the projection of one will retract the other, tumbler mechanisms for each of said dead bolts, a connection between said 45 tumbler mechanisms whereby an inside or outside key will actuate simultaneously said tumbler mechanisms and permit the projection and retraction of said dead bolts, means operable from the inside of the door only 50 and independent of a key for actuating said tumbler connection whereby both of said dead bolts may be operated by said independent means, in combination with a plurality of keys capable of operating one of the bolts from the outside, and a blocking out device to prevent the insertion of one of said keys from the outside into operative position when another of said bolts has been projected by means from the inside. 55
